AUTOMOBILE INSTRUMENT PANEL

Piergiorgio Tronville, Heilbronn, Germany, and Pio Manzu, Turin, Italy, assignors to Deutsche Fiat Aktiengesellschaft Heilbronn, Baden-Wurttemberg, Germany

Filed Mar. 27, 1969, Ser. No. 16,489

Claims priority, application Germany Oct. 3, 1968

Term of patent 14 years

Int. Cl. D12—14

U.S. Cl. D14—6

FIG. 1 is a front view of an automobile instrument panel showing our new design.

FIG. 2 is a sectional view thereof taken along the line 2—2 of FIG. 1.

FIG. 3 is a sectional view thereof taken along the line 3—3 of FIG. 1.

FIG. 4 is a front perspective view showing the heater control face element.

The elements of an automobile shown in broken lines are included for illustrative purposes only. The surrounding structure in FIG. 4 is broken away for convenience of illustration.

We claim:

The ornamental design for an automobile instrument panel, as shown and described.
